UNITED STATES PATENT OFFICE

PETER J. MARCH, OF LAS VEGAS, NEVADA

SPRING HINGE

Application filed May 25, 1932. Serial No. 613,513.

The invention relates to a hinge and more particularly to a spring hinge, or spring butt adjuster.

The primary object of the invention is the provision of a hinge, wherein the spring for the same is mounted in a novel manner so that such spring can be adjusted to tension the leaves of the hinge or the said spring uncoupled so that the hinge will be devoid of spring action in the use thereof, the manner of adjustment of the spring being novel in form and is manually regulated.

Another object of the invention is the provision of a hinge of this character, wherein the spring in association therewith is concealed and is regulated by an adapter so that the spring can be utilized for the purpose of having the hinge function as a door closer.

A further object of the invention is the provision of a hinge of this character, wherein the same is mountable in different ways between a stationary and swinging part and will permit the swinging of such swinging part either under tension or without such tension, the hinge in its entirety being of novel construction.

A still further object of the invention is the provision of a hinge of this character which is extremely simple in construction, thoroughly reliable and efficient in its purpose, possessing but few parts, strong, durable, and inexpensive to manufacture.

With these and other objects in view, the invention consists in the features of construction, combination and arrangement of parts as will be hereinafter more fully described in detail, illustrated in the accompanying drawing, which discloses the preferred embodiment of the invention, and pointed out in the claims hereunto appended.

In the accompanying drawing:

Figure 1 is an elevation of a hinge constructed in accordance with the invention, the spring barrel being in section.

Figure 2 is a sectional view on the line 2-2 of Figure 1 looking in the direction of the arrows.

Figure 3 is a top edge view.

Figure 4 is a sectional view on the line 4-4

of Figure 1 looking in the direction of the arrows.

Figure 5 is a sectional view on the line 5-5 of Figure 1 looking in the direction of the arrows.

Figure 6 is a detail plan view of an adjunct. Similar reference characters indicate corresponding parts throughout the several views in the drawing.

Referring to the drawing in detail, the spring hinge comprises a pair of leaf plates 10 and 11 respectively, these provided with fastener holes 12 to accommodate screws or other fasteners for the securing of said plates upon a stationary and swinging part.

The plates 10 and 11 intermediate thereof are provided with matched cut-out portions 13, while the plate 10 is formed with the upper and lower pintle eyes 14 and 15 respectively and the plate 11 is formed with a pair of spaced upper pintle eyes 16 and a lower pintle eye 17 respectively. Engaged with the upper pintle eyes 14 and 16 is a pintle 18 constituting the spring adjuster having an outer head 19 carrying a finger hold or wing 20 and likewise engaged in the pintle eyes 15 and 17 is a pintle 21, the same formed with an inner squared head 22, while the outer end is threaded at 23 to accommodate a terminal nut 24.

The squared inner end 22 of the pintle 21 is fitted in a correspondingly shaped center opening in a cone 25 about which is welded the outer coil of a convoluted tensioning spring 26, the other end of which fits and is welded on a cone 27 threaded on the inner end of the pintle 18, the spring being located between said cones.

Surrounding the spring 26 is a barrel 28 which confines the spring and also receives in opposite ends thereof the cones 25 and 27, this barrel 28 being located within the cut-out portions 13 in the plates 10 and 11.

The cone 27 is formed with ratchet teeth 29 co-acting with ratchet teeth 30 on the lowermost pintle eye 16 and in this fashion a latching coupling is had therebetween.

The pintle eye 15 next to the cone 25 is formed with a squared socket 31 for the squared end 22 of the pintle 21 so that when

the cone 27 is latched with the eye 16 the leaf plates 10 and 11 will be tensioned by the spring 26. On adjustment of the pintle 18 in a manner to move the cone 27 out of engagement with the pintle eyes 16 the spring 26 will untension the plates 10 and 11 and the hinge will function as the ordinary non-spring hinge.

When the spring 26 is coupled by the cone 10 27 with the pintle eyes 16 the hinge will function as a door or other swinging part closer.

It should be apparent that in the use of the hinge structure hereinbefore described the necessity for the employment of friction casement adjusters or other similar adjusters for 15 either casement windows, doors or the like will be avoided.

What is claimed is:—

1. A hinge of the character described comprising leaf plates, pintles pivotally connecting the plates together and spaced apart, one pintle being fixed with one plate, clutch means adjustably connected with the other pintle and engageable with the other plate, 20 a coiled tensioning spring acted upon by said last named means to render the same active or inactive, and a barrel surrounding the spring.

2. A hinge of the character described comprising leaf plates, pintles pivotally connecting the plates together and spaced apart, one pintle being fixed with one plate, clutch means adjustably connected with the other pintle and engageable with the other plate, 25 a coiled tensioning spring acted upon by said last named means to render the same active or inactive, a barrel surrounding the spring, and means for adjusting the pintle connected with said first named means to render the 30 spring active or inactive.

3. In a hinge of the character described, a pair of leaf plates, pintle eyes formed on said plates, pintles engaged in said eyes for 35 swingingly connecting the plates, means on one pintle to make the same fast with one plate, means on the other pintle to make the same fast with the other plate, means for releasing said last named means, and a coiled spring connected with the first and last 40 named means.

4. In a hinge of the character described, a pair of leaf plates, pintle eyes formed on said plates, pintles engaged in said eyes for 45 swingingly connecting the plates, means on one pintle to make the same fast with one plate, means on the other pintle to make the same fast with the other plate, means for releasing said last named means, a coiled spring connected with the first and last 50 named means, and a barrel encasing the 55 spring and held between said pintle eyes.

In testimony whereof I affix my signature.

PETER J. MARCH.
